HEART-LUNG RESCUE UNIT

Carl Hewson, 90 Myrtle St., Marshfield, Mass.

Filed July 14, 1964, Ser. No. 80,866

Term of patent 14 years

(Cl. D83—1)

FIG. 3

FIG. 1 is a perspective view of a heart-lung rescue unit showing my new design;

FIG. 2 is a bottom view on a slightly reduced scale; and

FIG. 3 is a bottom perspective thereof, with portions omitted for convenience of illustration only.

The side not shown in FIG. 1 is the same as the side which is shown.

The dominant features of my design reside in the portions shown in full lines.

I claim:

The ornamental design for a heart-lung rescue unit, as shown, and described.
